UNITED STATES PATENT OFFICE.

JAMES C. LEDBETTER, OF BROOKLYN, NEW YORK, ASSIGNEE, BY MESNE ASSIGNMENTS, TO THE PROSPERITY COMPANY, INC., OF SYRACUSE, NEW YORK, A CORPORATION OF NEW YORK.

GARMENT STEAM AND AIR PRESS.

Application filed October 30, 1924. Serial No. 746,724.

This invention relates to garment presses and more particularly to pressing machines having a pressing member or jaw improved in respect to combination steam spraying and air drying facilities.

A main object of the invention is to produce improvements over the United States Weinberger Patent 1,193,093 and United States Andrée Patent 1,369,769. The press disclosed in the Weinberger patent, while having air drying means, is not provided with steam spraying facilities in the same pressing member with the air drying means; and an object is to improve over that construction and provide both steam spraying and airing means in one and the same chamber. The Andrée machine as disclosed in his patent is provided with a combination steam spray and airing jaw or pressing member, but the airing and steam spraying chamber are one and the same chamber which requires that the air be circulated through the same chamber which circulates the steam, and so it follows that the intensive circulation of cool air through the steam spraying chamber causes the said steam chamber to be cooled off thereby producing a loss in efficiency by reason of the fact that an excessive amount of steam is required to operate the Andrée machine, and so it follows that an object of my invention is to produce a pressing member or jaw structure having separated air and steam spraying chambers though providing said chambers in one and the same pressing member.

Furthermore an object is to improve over the Andrée patent in respect to the means for heating the air before it passes through the garment, for while Andrée explains that an advantage in his machine rests in the fact that the air is heated before being blown up through the buck and through the garment, it is found that in reality this condition does not follow in actual practice because the heat radiating surface along which the air travels is very small; but I so design and construct my improved pressing jaw that extremely hot air is ejected from the foraminous press plate through the garment to dry same.

50 The accompanying drawing illustrates one form of the invention; and it is to be understood that changes may be made without departing from the principle of the invention.

The view illustrates a fragmentary side

elevation of a pressing machine with the head partly up and with the other pressing member or jaw, as for example the buck, illustrated in cross section to clearly show the detailed construction of the improvements.

60 Referring further to the drawings, there is shown the usual press frame 10 on which a press lever 11 is pivoted at 12 and any suitable mechanism is provided for swinging the press lever 11 up and down to close the head 13 upon the buck 14. The head and buck 13 and 14 are steam heated and either one or both of the pressing members may be constructed in accordance with the principle of this invention, but the lower press member 70 or jaw, usually known as the buck, is herein chosen to illustrate this invention.

75 The buck 14 comprises a single piece casting or it may be welded up of steel plate material and has the necessary partitions by 75 which the buck is divided off into the respective heat and spray chambers. A partition wall 15 provides a closed heating chamber 16 made with pipe connecting ducts 17 by which feed and return steam pipes 18 lead 80 to and from the buck-heating chamber 16 in order that a supply of live hot steam be continually circulated through the buck heating chamber 16.

85 A partition 20 forms a spray chamber 21 for steam or air spraying purposes, as the case may be, and this chamber 21 may be comparatively shallow or of any shape and proportions as desired. The wall 20 may be made with integral upstanding bosses 22 90 perforated as at 23. The said perforated bosses 22 are uniformly distributed over the upper surface of the wall 20 and out through which steam or air is ejected onto the garment. In the present instance the spray 95 chamber 21 is intended for the circulation of air therethrough because this chamber is adjacent the large steam heating chamber 16 the upper wall 15 of which heats the air chamber 21 to such high temperature that 100 the air passing upwardly through the chamber 21 becomes highly heated.

105 The plurality of perforated bosses 22 support a foraminous press plate 25 slightly spaced from the wall 20 thereby producing another foraminous shallow chamber 26 entirely separated from the first named air spray foraminous chamber 21. The plate 25

forming the upper pressing surface of the buck is provided with a separate set of perforations 27 which lead directly to the steam spray chamber 26. This press plate 5 is likewise perforated at 28, and the many perforations 28 register with the perforations 23 in the bosses. It is now apparent how the perforations 28 lead to the air spray chamber 21 and the perforations 27 lead to the steam spray chamber 26, and each chamber 10 is independent of the other though leading through the same foraminous plate. The bosses 22 constitute ducts which lead through the steam spray chamber 26 to the air spray chamber 21 and connect the latter 15 with the press plate 25.

An air pipe connecting duct 30 leads through the steam heating chamber 16 and enables an air pipe 31 to connect directly 20 with the air spray chamber 21. The pipe 31 is intended to be connected with a suction or blowing fan. Preferably the pipe 31 is connected with a pressure blower in order that air under pressure be delivered into the 25 air spraying chamber 21 where the air comes in contact with the hot walls of the buck causing the air to be highly heated as it sprays upwardly through the perforations 23-28.

30 A pipe duct 33 opens into the steam spray chamber 26 and leads through the other two chambers 21 and 16 thereby enabling a steam pipe 34 to be directly connected to the steam spray chamber 26. The pipe 34 connects 35 with the boiler or more conveniently connects with the steam feeding pipe 18.

A steam spray valve 35 is included in the pipe line 34 and a release rod or mechanism 36 is so arranged that an operator working 40 the press may at will open the valve 35 to discharge live steam from the supply pipe 18 up into the steam spray chamber 26. In the operation of an improved pressing machine of this character, it is significant that 45 the air spray chamber 21 and steam spray chamber 26 are separated. It follows, therefore, that no steam is permitted to pass through the air chamber, and conversely, no air is permitted to pass through the steam 50 chamber.

By segregating the steam chambers into two separated compartments as disclosed in this invention, the internal walls of the steam spray chamber are never cooled off by 55 air rushing therethrough since the air is restricted to circulation through another chamber. It follows that a pressing machine of this type is more efficient, and causes the ejection of steam and air or other spray fluid in more pure and unadulterated state onto the garment for the treatment and conditioning thereof.

What I claim is:-

60 1. A garment pressing machine comprising in combination, cooperating pressing 65

members adapted to open and close on the work, one of the pressing members being provided with a pressing surface and a fluid heating chamber, pipe connections established therewith to convey heat to and from 70 the heating chamber, said pressing member also being provided with two separated shallow chambers, an air pipe connected to one of the shallow chambers, and a steam pipe 75 connected to the other shallow chamber, both of said shallow chambers being perforated through the pressing surface and out through which steam and air flows, and said perforations connecting with the respective shallow chambers so that the steam and air 80 always flow through separated respective perforations.

2. An improved garment press comprising in combination, pressing jaws and means to open and close the press on the work, one 85 jaw being provided with three chambers, one of which is a sealed chamber for heating purposes, another chamber for steam spraying purposes, and a third chamber for airing the garment, each of the last two chambers named being provided with an upper perforated press plate through which air and steam is discharged, partition walls included in the jaw by which the aforesaid chambers are formed, and perforations leading from the press plate to the second and third chambers named. 90

3. A combination steam and air garment press comprising cooperating pressing members, one of the members being made hollow, 100 a solid partition made in the hollow chamber forming a heating chamber, a foraminous partition made in the chamber above the solid partition thereby forming a spray chamber, a foraminous press plate forming 105 the working surface of the member providing another spray chamber, a steam pipe connecting with one spray chamber, an air pipe connecting with the other spray chamber, and steam heating pipes connected with 110 the said heating chamber.

4. A steam heated pressing member for use in connection with garment presses, comprising a hollow casting having a closed heating chamber made with pipe ducts to 115 which is attached steam feed and steam return pipes, a spray chamber formed adjacent the heating chamber, a plurality of perforated bosses cast integral with and rising above the spray chamber, a plate disposed 120 over the perforated bosses thereby forming a second spray chamber, said plate having perforations registering with the aforesaid perforated bosses leading to the first named spray chamber, another set of perforations 125 provided in the plate leading to the second spray chamber and being independent of the first named perforations, a pipe duct opening into the first named spray chamber and extending through the heating 130

chamber and first spray chamber, and another pipe duct connecting with the other spray chamber.

5. An improved garment press jaw heated by steam and being provided with steam and air spray means, a press plate on said jaw having two independent sets of perforations formed in its working face, said jaw being provided with a heating chamber, said 10 jaw being provided with an airing chamber adapted to discharge air through one set of the aforesaid perforations, and a steam spraying chamber adapted to discharge steam through the other set of perforations, 15 and said steam spraying chamber being separated from said airing chamber to prevent the air from cooling the steam spray chamber.

6. A pressing machine jaw comprising, a 20 pressing member having a perforated working face on which is placed the work, said member provided with three shallow chambers of substantially the same area, two parallel partitions one above the other inside 25 the member by which is formed the three chambers, some of the aforesaid perforations opening directly into one chamber, means connecting the other perforations to another chamber, and means for supplying fluid to 30 each chamber.

7. A press jaw provided with a heating chamber and means to supply heat thereto, and provided with separate air and steam spray chambers and means to supply a spray

medium thereto, a perforated press plate 35 disposed over both of the spray chambers, and ducts leading from the perforated plate through one spray chamber and connecting with the other spray chamber.

8. A garment pressing machine comprising in combination, cooperating pressing members adapted to open and close on the work, one of the pressing members being provided with a pressing surface and a fluid heating chamber, pipe connections to convey 40 a heating medium to and from the heating chamber, said pressing member also being provided with two separate means for receiving air and steam spray fluids, a pipe 45 connected to one of the means, and a pipe connected to the other means, and both of 50 said means being perforated through the pressing surface and out through which the different kinds of spray media flow.

9. An improved garment press jaw heated by steam and having steam and air spray means, a pressing surface on said jaw and provided with independent sets of spray perforations, said jaw being provided with a heating chamber, said jaw being further 55 provided with an airing chamber and means to move air through one set of the aforesaid perforations, and a steam spraying chamber 60 opening to the other set of perforations and adapted to spray steam therethrough.

65 In testimony whereof I affix my signature.

JAMES C. LEDBETTER.
